PLASTIC COVER FOR CONTAINERS

David Goldrosen, Worcester, Mass.

Application September 28, 1951, Serial No. 16,765

Term of patent 14 years

(Cl. D58—26)

To all whom it may concern:

Be it known that I, David Goldrosen, a citizen of the United States, residing at Worcester, in the county of Worcester and State of Massachusetts, have invented a new, original, and ornamental Design for Plastic Cover for Containers, of which the following is a specification, reference being had to the accompanying drawing, forming part thereof.

Fig. 1 is a top plan view of a plastic cover for containers, showing my new design;

Fig. 2 is a top plan view showing the lid opening and the lid in open position, and

Fig. 3 is a sectional view taken on the line 3—3, and showing the lid partially open.

I claim:

The ornamental design for a plastic cover for containers, as shown.

DAVID GOLDROSEN.
